UNITED STATES PATENT OFFICE.

JENS OLSEN, OF PORTLAND, OREGON.

FASTENER FOR PAINT-CANS.

No. 829,169.

Specification of Letters Patent.

Patented Aug. 21, 1906.

Application filed September 12, 1902. Serial No. 123,200.

To all whom it may concern:

Be it known that I, JENS OLSEN, a citizen of the United States, and a resident of Portland, in the county of Multnomah and State 5 of Oregon, have invented a new and useful Improvement in Fasteners for Paint-Cans, of which the following is a specification.

My invention is especially designed for rendering safe the transporting and carrying 10 about paint and oils, but may be also conveniently used for other liquids.

My invention has for its object to obtain a can of inexpensive structure; means by which the cover may be securely fastened on the 15 body of the can, so that the latter may be carried about and shipped without apprehension of its contents escaping from under its cover and spilling over its sides.

The construction of my invention is as illustrated in the accompanying drawings, hereby referred to as a part of this specification, the 20 reference characters in which designate the parts described.

In such drawings, Figure 1 is a vertical longitudinal section. Fig. 2 is a top view of the can with cover removed. Fig. 3 is a partial longitudinal section showing the flange-like edges *e* of the protruding center *e*² of the cover as sloped instead of perpendicular, so 25 as to be able to draw the cover tightly on the rim of the can. Fig. 4 is an elevation of one side of my can with its cover secured in place; and Fig. 5 is a partial perspective view of my 30 can and cover, the last two figures illustrating more clearly the construction and operation of the locking-bails *d*.

The body of my can consists of an outer casing of wood *a*, having an interior metal lining *a'*. Near the top on the exterior of the 40 two sides are provided projecting cleats or strips *b b*, having apertures *c* through which to insert the open or loop ends *d'* of the bails *d*, fastened to two sides of the cover. The cleats or strips *b b* are also convenient at 45 times for lifting the can when filled and heavy. The cover *e* is made of wood and the body-surface thereof at its four edges or sides is recessed or rabbeted to leave flange-like edges and a protruding middle portion *e*², 50 fitting into the opening of the can. The sur-

faces *e*³ may be perpendicular or sloped, as shown in Fig. 3. The latter construction has special advantage in this, that it adapts the cover to be drawn tightly down on the rim of the can, in so doing effecting a tight closure 55 and insuring the liquid contents of can will not be spilt in transportation. On top of the cover is provided a handle or carrying-bail *g*, and to two opposite sides of the cover are attached by staples *g'* the locking-bails *d*. The 60 construction of the latter is more clearly seen in Fig. 5. Such locking-bails are made of wire twisted and bent, as shown, and so that the upper parts of these locking-bails will lie flat upon the edges of the cover and the open 65 or loop extremity thereof be turned at a right angle, so as to be inserted in the apertures *c* of the cleats or strips *b b* in position to receive the wedges *f*, which are made with tapering lower edges. By driving in the latter 70 the cover is drawn down tight and secured. Staples might be used in place of the cleats or strips *b b*; but they would not be as serviceable. I prefer the described construction of 75 my locking-bails *d*, because the arrangement thereof makes them stronger and more durable in service. The projecting cleats or strips have a special object. The wedges being inserted under such cleats or strips, they 80 are covered by the latter and protected from being knocked against and loosened while in transportation.

When my can filled with paint is to be shipped any distance, the crevice between the rim of the can and the bottom of the 85 cover may be rendered absolutely tight by spreading on such rim a layer of putty, which a painter always has handy, and then securing the cover in the way described.

Having fully described my invention, now 90 what I claim, and desire to secure by Letters Patent, is—

In a portable can for liquids, the combination with the body and the cover, of a fastening comprising horizontally-projecting cleats 95 or strips on the exterior of opposite sides of the body and made with vertical apertures, locking-bails fastened to the cover, and adapted to be inserted through the apertures of the cleats and to extend below the latter; 100

the ends of said bails being provided with loops arranged to project at right angles from the sides of the body, and tapering wedges inserted under the cleats in said loop ends of the bails, to force and hold the cover down on the rim of the body, the projecting sills also serving to protect the wedges inserted under them against accidental displacement.

In testimony whereof I have hereunto affixed my signature, in the presence of two ^{to} witnesses, this 15th day of August, 1901.

JENS OLSEN.
